UNITED STATES PATENT OFFICE.

JOHN COYLE, OF BALTIMORE, MARYLAND, ASSIGNOR TO CONTINENTAL CAN COMPANY, INC., OF NEW YORK, N. Y., A CORPORATION OF NEW YORK.

SEAMING HEAD FOR CAN-CLOSING MACHINES.

Application filed March 15, 1927. Serial No. 175,503.

The invention relates to new and useful improvements in seaming heads for can closing machines, and more particularly to a seaming head provided with a chuck and a body portion rotatable relative to each other, which body portion carries seaming rolls for rolling the can end and flange on the can body into a double seam.

An object of the invention is to provide a seaming head of the above type wherein the second operation seaming roll is forced into contact with the metal for rolling the same into a double seam, by a cam follower which bears against a yieldable abutment, wherein means is provided for positively limiting the movement of the abutment.

A further object of the invention is to provide a device of the above type wherein the cam follower abutment and limiting means therefor can be bodily adjusted for varying the tightness of the seam.

A further object of the invention is to provide a seaming head of the above type wherein the seaming roll is carried by a seaming lever and the seaming lever is actuated by a cam follower resting against an abutment which in turn bears against a spring, and wherein means is provided for limiting the movement of the abutment through the action of the spring.

A still further object of the invention is to provide a device of the above type wherein the cam follower, the abutment and spring may be bodily shifted on the seaming lever for varying the tightness of the seam.

These and other objects will in part be obvious and will in part be hereinafter more fully disclosed.

In the drawings which show by way of illustration one embodiment of the invention—

Figure 1 is a sectional view through a seaming head embodying the improvements, the section being taken from the second seaming operation rolls;

Fig. 2 is an enlarged sectional view of one end of one of the seaming levers, and

Fig. 3 is a face view of the upper end of the seaming lever.

The invention is directed to a seaming head having a body portion in which is mounted a chuck spindle carrying a chuck. Either the chuck is rotated to rotate a can which is to be closed, or the chuck is stationary, in which case, the body portion of the

head is rotated which causes the seaming rolls carried by the heads to travel about the can. Mounted on this head are seaming levers. The seaming levers are preferably arranged in pairs, one pair of levers carrying the first operation seaming rolls and the other pair of levers carrying the second operation seaming rolls. Each seaming lever is provided with a cam follower. Mounted on the spindle and movable endwise thereon, are cams, one of which cooperates with the first operation seaming rolls and the other with the second operation seaming rolls. The parts as described are similar in construction to those shown in the patent granted I. F. Warne, June 24, 1919, No. 1,307,888, and further detail description thereof is not thought necessary.

The present invention has to do with the means for operating the second operation rolls. Before describing the invention in detail, brief reference will be made to the parts shown in the drawing which are of well known construction. The seaming head includes a body portion 1 in which is mounted a spindle 2 carrying a chuck 3. Either the chuck or the head rotate, but not both. Mounted on the head 1 is a pair of second operation seaming levers 4, 4. These levers are pivoted at 5 to the body portion of the head. Each lever is provided with a seaming roll 6 having a seaming groove 7, and also having an annular channel 8 which receives an annular projecting rib 9 on the chuck. This inter-engagement of the seaming rolls and chuck is of the well known construction. At the upper end of the seaming lever there is an opening 10 which extends all the way through the lever. Located in this opening 10 is a cam follower 11. The cam follower 11 has a tapered shoulder 12 which is adapted to cooperate with a cam 13 movable vertically on the spindle 2. A pin 14 carried by the seaming lever projects into a groove 15 in the cam follower 11 and prevents the same from rotating in the opening 10.

This opening 10 is threaded, and is adapted to receive a sleeve 16 having the outer end closed as at 17. There is an opening 18 through this closed end. The follower 11 is provided with a chamber 19. Located in this chamber 19 is an abutment 20 carried by a stem 21 which passes through the opening 18. Located in the sleeve 16 and ex-

tending into the chamber 19 is a spring 22. This spring is preferably made on a lathe by cutting a cylinder so as to form the spring. The spring is very stiff and is 5 practically free from tension during the second operation on the double seam until the side seam is reached, at which time this spring 22 yields to allow the seaming roll to pass over the side seam. A nut 23 is 10 threaded on to the stem 21 and holds the abutment snug up against the spring 22. A lock nut 24 will hold the parts in this position. This spring 22 may be put under slight tension, if desired, but it is not intended that the spring should function to 15 any extent, except when passing the side seam. The sleeve 16 can be adjusted in the lever and held in adjusted position by a locking collar 25 which may be held from turning by a locking wire 26 of the usual construction.

In the operation of my improved head, the cam follower is adjusted so that when the cam 13 swings the lever into contact 25 with the metal parts, the second operation will be performed in the double seam. At all points in the double seam, except when crossing the side seam, the sleeve 16 is adjusted so that the follower 11 will not be 30 moved relative to the lever to any extent. When, however, the side seam is reached, then the follower is yieldable and will move so as to permit the seaming roll to pass the side seam. When it is desired to increase 35 the tightness of the seam, the sleeve 16 is adjusted so as to move the follower 11 to the left, as viewed in Fig. 2; and on the other hand, when the seam is too tight, then the follower can be adjusted in the opposite 40 direction. During this adjustment of the follower, the abutment and the spring are likewise shifted in the follower, and this is accomplished without in any way changing the tension on the spring. It will be seen, 45 therefore, that I have provided a cam follower for operating the seaming roll, which has associated with it, a yieldable abutment, and means is provided whereby the follower and yieldable abutment can be adjusted 50 bodily without varying the tension of the spring in back of the follower, or in any way disturbing the set position of the parts. When the spring is properly placed so as to provide, in substance, a solid abutment during 55 the seaming operation at all points, except when crossing the side seam, and to provide a yielding abutment when crossing the side seam, the tightness of the seam may be varied by shifting the sleeve without disturbing these set conditions.

A spring 26 is placed between the body portion of the seaming head and the lower end of the seaming lever 4. This is a light spring and is for the purpose of normally 60 holding the seaming rolls in their extreme

outer position when the cam 13 is raised. It will be noted that the spring 22 does not swing the lever 4 so as to bring the seaming roll into contact with the metal parts. The spring operates against the abutment 20, and this limits the action of the spring. Therefore, the spring 26 does not work against the heavy spring 22; neither does the centrifugal force which moves the rolls outwardly when the head is rotating, operate against this spring 22.

By the construction above described, I am able to use a very heavy spring for supporting the abutment. It is well known that during the forming of the double seam, the metal rolling into the seam flows ahead of the seaming roll. As a result, when the side seam is reached, this metal flowing ahead of the rolls will pass up on to the side seam, and often builds up at the side seam so as to increase the thickness of the metal for the roll to pass over, and the result is that the seaming roll does not bring the metal into a tight seam just beyond the side seam, and V openings in the seam are produced, which are likely to leak. By my improved construction, however, where the spring is, in effect, a solid abutment during the formation of the double seam at all points thereof until the side seam is reached, and where the seaming lever is capable of yielding under a very heavy spring tension to pass the side seam, the metal is forced into a tight seam, not only across the side seam, but at both sides of the side seam.

While I have described the invention as particularly applicable to the means for operating the second operation seaming lever, it will be understood, of course, that it may be used in connection with the first seaming lever operation. The cam follower resting against the abutment, is held in substantially fixed position during the rolling of the metal into the seam, except when the side seam passes beneath the seaming roll. Inasmuch as the abutment is limited in its movement, and the spring is a very heavy spring, the device forming the present invention may be used with great advantage with either seaming lever.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. A seaming head for closing machines including a chuck, a body portion, said chuck and body portion having a relative rotation, a seaming lever carried by the body portion, a seaming roll mounted on said seaming lever, a cam mounted on the seaming head and movable relative thereto for

operating the seaming lever, a cam follower carried by said seaming lever, a yieldable abutment carried by the lever and engaging said cam follower, and means for positively 5 limiting the outward movement of said yieldable abutment.

2. A seaming head for closing machines including a chuck, a body portion, said chuck and body portion having a relative rotation, a seaming lever carried by the body portion, a seaming roll mounted on said seaming lever, a cam mounted on the seaming head and movable relative thereto for operating the seaming lever, a cam follower 10 carried by said seaming lever, a yieldable abutment carried by said lever and engaging said cam follower, means for positively limiting the outward movement of said yieldable abutment, and means for adjusting said 15 cam follower and abutment on said lever for varying the tightness of the seam.

3. A seaming head for closing machines including a chuck, a body portion, said chuck and body portion having a relative rotation, a seaming lever carried by the body portion, a seaming roll mounted on said seaming lever, a cam mounted on the seaming head and movable relative thereto for operating the seaming lever, a cam follower 20 carried by said seaming lever, an abutment against which said follower bears, a spring carried by the lever and bearing against said abutment, a support carried by said lever against which said spring bears, and means 25 passing through said support and connected to the abutment for limiting the outward movement thereof.

4. A seaming head for closing machines including a chuck, a body portion, said

chuck and body portion having a relative 40 rotation, a seaming lever carried by the body portion, a seaming roll mounted on said seaming lever, a cam mounted on the seaming head and movable relative thereto for operating the seaming lever, a cam follower 45 carried by said seaming lever, an abutment against which said follower bears, a spring carried by the lever and bearing against said abutment, a support carried by said lever 50 against which said spring bears, means passing through said support and connected to the abutment for limiting the outward movement thereof, and means for shifting the position of said support in said lever.

5. A seaming head for closing machines including a chuck, a body portion, said chuck and body portion having a relative rotation, a seaming lever carried by the body portion, a seaming roll mounted on said seaming lever, a cam mounted on the seaming head and movable relative thereto for operating the seaming lever, a cam follower 55 carried by said seaming lever, said follower having a chamber at the inner side thereof, an abutment located in said chamber against which the follower rests, a sleeve having an adjustable connection with the seaming lever and adapted to receive and guide a portion of the follower, and a spring intermediate 60 the abutment and the inner end of the sleeve, said abutment having a stem passing through the end of the sleeve, and a nut on the end of said stem for limiting the movement of the abutment through the action 65 of said spring.

In testimony whereof, I affix my signature.

JOHN COYLE.
